WATERPROOFING OF MASONRY WALLS

Arved L. Larson, Rockville Centre, N. Y.

Application December 9, 1933, Serial No. 701,630

5 Claims. (Cl. 72—127)

The present invention relates to water-proofing of masonry walls.

Brick walls, composed of brick and mortar, laid in the customary manner, have been found to be so porous that some expedient must be resorted to for the exclusion of water. The bricks themselves are porous and cracks and seams of greater or less size are always present in the mortar. These seams are caused by carelessness in the laying of the mortar, shrinkage of the mortar, vibration, settling, or for other reasons. The net result of these conditions is likely to be a leaky wall. Rain water, especially where driven by a hard wind, readily passes through these walls and ruins the finish applied to the walls.

Where no attempt is made to damp proof the wall itself, various expedients are resorted to to permit a dry surface to be had inside. The more common expedient is applying furring strips on the wall and then some form of lath to which plaster, mastic, or other surfacing is affixed. These add to the expense and waste room space.

The present invention contemplates the water-proofing of the masonry wall by impervious sheet material which is inserted in place in the wall as the mason lays up the wall. This material is so thin as to make no difference in the thickness of the wall and is placed so as not to impair the load bearing properties of the wall. It is not continuous through the height of the wall for such water-proofing would separate the wall into two partial walls and destroy cross bonding. The water-proofing material is in pieces, each piece affording protection to an area of the wall. Each such piece extends through a part of a horizontal joint, preferably where header courses overlap downwardly to the next header course, and upwardly far enough to protect the horizontal mortar joint to be left unprotected by the next higher piece.

The preferred material for this water-proofing is a preformed length of ordinary asphalt roofing felt. It is cut to length, formed to a Z-shape and placed on parged parts of the brick wall so as to protect the same and is then buried in behind the outer bricks. This material is inexpensive, completely water-tight, and when laid with lapped joints, becomes self-sealing under the pressure in the wall.

Other and further objects of the invention will appear as the description proceeds.

The accompanying drawing shows, for purposes of illustrating the present invention, one of the many embodiments in which the invention may take form, it being understood that the drawing

is illustrative of the invention rather than limiting the same. In this drawing:

Fig. 1 is a perspective view illustrating the building up of a brick wall embodying the present form of water-proofing, and

Fig. 2 is a perspective view of a water-proofing element.

In the drawing, the invention is illustrated in connection with the customary twelve inch "American bond" wall having header courses comprising an outer course of brick indicated at 10 and an inner course of brick indicated at 11, which overlap to provide a transverse bond, and five courses of stretcher brick, the front brick being indicated at 12a—e, inclusive, the middle brick 13a—d, inclusive, and the inner brick 14a—e, inclusive. The mortar joints are indicated by the letter M. The invention is, however, applicable to English, Flemish, or other forms of bonded wall, and where the wall is more than 12 inches thick, also to masonry walls having brick faces and tile backings.

In building up a solid brick wall it is first laid as to have the cross section indicated at the right hand side of Fig. 1. Here it will be noted that the wall has been completed at the bottom, and that a stack of inner stretchers and intermediate stretchers have been laid up in mortar and covered over by a course of inner headers 11.

In the drawing two additional courses of inner stretchers 14a, 14b are also indicated as having been laid. This is preferable but not an essential step in the preparing of a portion of the wall for water-proofing.

The front surfaces of the inner headers and intermediate stretchers, as well as the front surfaces of the inner stretchers (where already placed) are parged as indicated at P. In doing this a thin coating of mortar is spread along these surfaces for a suitable length of the wall. The wall is then ready for the Z-shaped water-proofing element W, which may be placed in position by the worker. These pieces are placed the entire length of this level of the wall and are preferably overlapped as indicated at 20. After they have been laid, the front stretchers and headers are laid up in mortar joints, as usual, to bring the front part of the wall up to the level of the next course of outer headers 10. The inner and intermediate stretchers and inner headers are then built up again and parged to receive the next piece of water-proofing material.

It will be noted that the water-proofing material herein shown extends downwardly through all the vertical mortar joints between two superposed

outer headers and that it extends through the portion of the horizontal joint between the lapped headers as well as up through the portion of the vertical joint adjacent the inner stretchers immediately above the inner headers. In this way 5 there is an overlapping of the vertical portions of the water-proofing means so that all the horizontal joints in the brick wall are protected and so that no water can possibly pass through the wall.

10 Various forms of thin sheet material of an impervious nature may be used. In some cases metal sheet is satisfactory but it is preferably provided with suitable corrugations or roughening so that 15 mortar will adhere to it. The preferred material, however, is a preformed sheet of ordinary asphalt roofing, or tarred felt. This material comes in widths which are convenient to handle and can be readily cut and bent to the desired shape. The 20 overlapped edges are self-sealing as the tarry surface of the roofing felt adheres under the pressure which will be developed in the wall.

It will be noted that a wall waterproofed as 25 above described, has unimpaired bearing strength and that the cross bonding by regular brick to mortar joints is carried out throughout a large 30 part of the wall. It will also be noted that the water-proofing material does not completely destroy cross bonding.

35 Where asphalt roofing felt or similar materials are used, the wall is insured against the development of shrinkage cracks or seams, for the adhesion of mortar to these materials is not so great as to prevent such slippage as will permit the water-proofing material to stretch and accommodate itself.

What is claimed is:

1. A solid brick wall having header and 40 stretcher courses in each face thereof with the header courses thereof lapped transversely, there being horizontal mortar joints between the courses of brick and vertical mortar joints between opposite header and stretcher courses, and imperforate water-proofing means extending across the portion of 45 the horizontal joint between lapped header bricks, downwardly through the vertical mortar joint in line with the front face of the inner headers so as to cross all the horizontal joints above the next lower outer header course and terminating adjacent said lower header course, and 50 upwardly behind the inner end of the outer header brick of the lapped courses and across the horizontal mortar joint next above.

55 2. A solid brick wall having header and stretcher courses in each face thereof with header courses lapped transversely, and all held together with mortar, and impervious water-proofing ele-

ments of Z-shape, said elements being thin and occupying substantially the entire height of the vertical mortar joint spaces over the middle of the outer header courses, a portion in excess of one brick in height of the vertical mortar joint space above the middle of the inner header courses and the portion of the horizontal mortar joint space where the headers are lapped, whereby water entering the wall through the front header and stretcher courses is prevented from passing to the header and stretcher courses protected thereby.

3. A preformed, Z-shaped water-proofing element for brick walls consisting of a sheet of impervious roofing felt bent to shape and having a 15 long vertical portion of a height equal to the height of a plurality of courses in a brick wall, a horizontal portion equal to one half the length of a brick and extending rearwardly from the upper end of the vertical portion, and a short rear 20 vertical portion whose height is greater than the thickness of a brick course and both adjacent mortar joints for water-proofing the inner portions of brick walls which have stretcher courses interrupted by header courses.

25 4. A solid masonry wall having inner and outer faces and comprising header and stretcher courses of brick in the outer face and a masonry backing extending to the rear face, there being vertical mortar joints behind the stretcher courses, horizontal mortar joints underneath the inner ends of header bricks and vertical mortar joints behind the inner ends of the header bricks, said latter vertical mortar joints extending upwardly above the header brick, and a plurality of imperforate 30 water proofing elements each extending upwardly through the first mentioned vertical mortar joint, rearwardly in the adjacent horizontal mortar joint and then upwardly through the second mentioned vertical mortar joint and terminating 35 above the lower edge of the next water-proofing element above.

5. A solid masonry wall having header and 45 stretcher courses of brick in at least one face thereof and a backing all held together by mortar, and impervious water-proofing elements of Z-shape, said elements being thin and occupying substantially the entire height of the vertical mortar joint space to the rear of said stretcher bricks, a portion in excess of one brick height of 50 the vertical mortar joint at the rear of the header brick and the portion of the horizontal mortar joint under the rear end of the header brick, whereby water entering the wall through said header and stretcher courses is prevented from 55 passing to the backing.
